UNITED STATES PATENT OFFICE.

CLARENCE E. FERGUSON, OF ROSENDALE, MISSOURI.

SPRING-HUB FOR AUTOS.

1,114,347.

Specification of Letters Patent.

Patented Oct. 20, 1914.

Application filed November 19, 1913. Serial No. 801,918.

To all whom it may concern:

Be it known that I, CLARENCE E. FERGUSON, a citizen of the United States, residing at Rosendale, in the county of Andrew and 5 State of Missouri, have invented certain new and useful Improvements in Spring-Hubs for Autos; and I do hereby declare the following to be a full, clear, and exact 10 description of the invention, such as will enable others skilled in the art to which it appertains to make and use the same.

This invention relates to new and useful 15 improvements in spring hubs, and has for its object the provision of a hub for a wheel with which it is possible to use a solid rubber tire and still maintain substantially the same resiliency as that afforded by the use of the usual pneumatic tire.

Another object of my invention is the provision of a novel combination and arrangement of parts by which the above object 20 may be accomplished.

A further object of my invention is to provide a means whereby the tension of the 25 spring in the wheel may be controlled to insure the proper operation of the device.

With the above and other objects in view, this invention consists of the novel combination and arrangement of parts as will be 30 more fully described in the following specification and accompanying drawings, in which—

Figure 1 is a side view of a portion of my improved hub with the cover plate removed. 35 Fig. 2 is an enlarged sectional view taken on line 2—2 of Fig. 1, Fig. 3 is a transverse sectional view taken on line 3—3 of Fig. 2, Fig. 4 is a detailed perspective view of one 40 of the elements making up the resilient member of my invention, and Fig. 5 is a detailed fragmentary perspective view of the coöperative elements.

Referring more particularly to the drawings, my invention consists in a novel combination of an inner bearing member and an outer spoke-carrying member which are connected by a plurality of spaced resilient yieldable members which are secured to the inner member and outer member at spaced 45 intervals.

Referring now to the drawings by characters of reference, the inner bearing member, which is indicated generally by the numeral 1, preferably comprises the ring having a centrally located bore 3 extending therethrough and for the reception of the

axle of the vehicle. Formed integral with the periphery of the ring 2, I preferably provide a plurality of ears 4 having the transversely extending apertures 5 formed therein. Each of the ears 4 is of less width than the thickness of the ring 2 and are centrally located with relation to the lateral extremities thereof to form recesses in which the arms of the resilient elements are adapted to 60 rest when the device is in use.

The spoke-carrying ring which is indicated as an entirety by the numeral 6, is provided at suitable intervals with the inwardly extending ears 7 which correspond 70 in every way to the ears 4 and are arranged to come in diametrically opposed alinement with relation to each other and in radial alinement with relation to the ears 4 on the ring 2. Each of these ears 7 is provided 75 with the transversely extending apertures 8, the use of which will be more fully herein-after described.

A pair of disks 9 and 10 which are supported by the ring 2, are suitably secured to 80 said ring and are adapted to act as cover plates whereby the resilient members may be protected from any dust or dirt through which the wheels of the vehicle are apt to travel.

Now proceeding to the description of the resilient members, which are best illustrated in Figs. 1, 2, 3, 4, and 5, the numeral 11 indicates the resilient members as an entirety. 85 Each of the resilient members is composed of substantially three elements designated respectively by the numerals 12, 13 and 14. The member 12 comprises the pair of spaced arms 15 and 16 having apertures in each end, one set of apertures in the end of the 90 arms 15 and 16 being adapted to receive the extensions 17 and 18 which are formed on the plate 19. The ends of the arms 15 and 16 opposite the plate 19 are pivotally secured to one of the ears 4 by means of the 95 bolt or rivet 20, as will be clearly seen on referring to Fig. 2. A suitable centrally located aperture 21 is formed in the plate 19 and is adapted to receive the shank of the bolt 22 when the device is in use.

The U-shaped member 13 which is illustrated in Fig. 4 preferably comprises the arms 23 and 24 which are connected at their ends by means of the bight portions 25 having a suitable centrally located aperture 110 26 formed therein for the reception of the shank of the bolt 22 when the device is in

use. Each of the arms 23 and 24 is provided with the longitudinally extending slots 27 and 28 respectively which are in direct alinement with the apertures 29 and 30, which are adapted to coöperate with the pin or rivet 21 which extends transversely through the aperture 8 formed in the ear 7. The resilient element of this member which is indicated as an entirety 10 by the numeral 14, preferably comprises the bolt 22 having the nut 32 coöperating therewith. A suitable washer 33 is placed over the bolt immediately between the nut and is adapted to form the abutment for the 15 upper end of the spring 34, the lower abutment of which is the bight portion 25 of the U-shaped member 13. A coiled spring 35 is interposed between the plate 19 and the bight portion 25 of the U-shaped member 13, and is adapted to normally exert pressure against these parts and thereby hold the same in spaced relation.

It will be clearly seen from the foregoing that in use the arms 15 and 16 of the member 12 are pivotally secured to one of the ears 4 on the inner bearing ring by means of the rivet or pivot pin 20. The spring 35 is then placed in position and the bolt 22 inserted through the aperture 21 30 in the plate 19. The U-shaped member 13 is then placed in position with the ears 17 and 18 of the member 19 extending through the slots formed in the arms of said U-shaped member. The shank of the bolt 22 35 then is passed upwardly through the aperture 26 of the bight portion 25 of the U-shaped member 13 and the spring 34 is then placed in position and held thereon by means of the washer 33 and nut 32. The arms of the U-shaped member 25 are 40 then pivotally connected to one of the ears 7 by means of the rivet or bolt 31 and it will be apparent that the outer ring 6 will be held in yieldable spaced relation with the inner ring 2 and should a shock occur 45 owing to roughness in the road over which the vehicle is traveling, it will be apparent that the springs 35 and 34 will co-operate to take up the vibrations and therefore 50 provide a substitute for the pneumatic tire which is now in use. It is to be understood however, that should it be so desired, the user may use this device in connection with the pneumatic tire and render riding 55 over rough roads much easier.

While in the foregoing I have described the preferred embodiment of my invention, I wish it to be understood that I may make such changes in the combination and arrangement of parts as may fall within the spirit and scope of the invention as defined in the appended claims.

Having thus described my invention, I claim:

1. In a device of the character described, 65 a pair of rings, a plurality of ears formed on said rings, a plurality of yieldable members secured to the ears, adapted to hold the same in spaced relation, each of said yieldable members comprising a pair of U- 70 shaped members, the free ends of the arms of said U-shaped members being connected to the ears on the rings, a bolt extending through the bight portion of the U-shaped members and in longitudinal alinement 75 with the arms thereof, a coiled spring interposed between the bight portions of the U-shaped members and surrounding the bolt and a second coiled spring interposed between the bight portion of one of the U- 80 shaped members and the end of the bolt, said second mentioned coiled spring being adapted to coöperate with the first mentioned coiled spring to hold the members in engagement. 85

2. In combination with a pair of concentric spaced rings having ears formed thereon, yieldable members secured to said ears, said yieldable members comprising a pair of U-shaped members, one of said U-shaped members having slots extending longitudinally through the arms thereof, and a centrally located aperture in the bight portion thereof, the other U-shaped member comprising a pair of arms, a plate having a pair of extensions formed thereon, the arms being provided with apertures near their free ends, said apertures being adapted to receive the extensions on the plate, said plate also having a centrally located aperture adapted to register with the aperture in the bight portion of the first mentioned U-shaped member, the free ends of the arms of each of said U-shaped members being provided with apertures by means of which 90 the same may be pivotally secured to the ears on a ring, a compression coiled spring interposed between the bight portion of the first mentioned U-shaped member and the plate of the second mentioned U-shaped 95 member, a bolt adapted to extend through the apertures in the plate and through the apertures of the bight portion of the U-shaped member, a second coiled spring superposed on the bight portion of the U- 100 shaped members and a washer secured to the bolt and forming the upper abutment 105 for the second mentioned spring. 110

In testimony whereof I affix my signature in presence of two witnesses.

CLARENCE E. FERGUSON.
